UNITED STATES PATENT OFFICE.

GEORGE I. KING, OF DETROIT, MICHIGAN, ASSIGNOR TO THE AMERICAN CAR AND FOUNDRY COMPANY, OF ST. LOUIS, MISSOURI.

DOUBLE-HOPPER-BOTTOM CAR.

SPECIFICATION forming part of Letters Patent No. 663,030, dated December 4, 1900.

Application filed August 17, 1900. Serial No. 27,161. (No model.)

To all whom it may concern:

Be it known that I, GEORGE I. KING, a citizen of the United States, residing at the city of Detroit, county of Wayne, State of Michigan, have invented a certain new and useful Improvement in Double-Hopper-Bottom Cars, of which the following is a full, clear, and exact description, such as will enable others skilled in the art to which it appertains to make and use the same, reference being had to the accompanying drawings, forming part of this specification, in which—

Figure 1 is a side elevational view of one end of my improved car. Fig. 2 is a top plan view of the same. Fig. 3 is a vertical sectional view. Fig. 4 is a top plan view of the underframing. Fig. 5 is an end elevational view. Fig. 6 is a cross-sectional view on line 6 6, Fig. 4. Fig. 7 is a detail view of one of the girder-plates used in connection with the center sill, and Fig. 8 is a detail sectional view on line 8 8, Fig. 1.

This invention relates to a new and useful improvement in car construction, being designed particularly for use in connection with double-hopper-bottom cars—that is, cars provided with a centrally-located cross-ridge intersected by the longitudinal ridge and providing, practically, four points of discharge for the load. So far as this is concerned, however, I do not wish to be understood as limiting my invention for use in connection with a double-hopper-bottom car, as the same can with slight changes be employed with what is known as a “single-hopper-bottom car”—that is, one wherein the cross-ridge is absent. Also certain features of the invention, particularly those relating to the underframing, can be employed for use with other types of cars—such as flat, gondola, and box cars. I will state that as a general proposition, irrespective of the particular style of car produced—that is, flat, gondola, box, or hopper-bottom cars—the framing employed for carrying the load may be of several different types. This framing where it is located under the floor-line may be in the form of wooden sills trussed by suitable rods, or the sills may be of commercially-rolled forms, with or without truss-rods, or of pressed forms, in which latter instance the sills are made deepest at their

middle portion, where they are subjected to the greatest strain, and shallower at their ends. Another type of car is one wherein the side walls are made of metal plates, forming a plate-girder, the side walls being designed to carry all or nearly all of the load. In this latter construction a center sill (or sills) is employed, and very light, if any, side sills are used. Still another type of framing is employed where room is permitted above the floor-level—as in gondola, hopper-bottom, and box cars. This type may be designated as the “trussed” type, wherein center sills are usually provided and side sills are also employed, these side sills forming the lower chords. A rail parallel to the side sills or slightly cambered, if desired, is also used to form the upper chord of the truss. Vertical posts are arranged between these rails, and diagonals are used to complete the structure. In these trussed forms the containing-walls of the car may be light wooden planking, as the load is carried entirely by the trussed structure. It is to this latter class or type of car that the present invention relates.

In the drawings, 1 indicates the center sills, which are preferably made of commercially-rolled channels with their flanges presented inwardly.

2 indicates the end sill, which may be a casting, and 3 the side sills, said side sills being preferably of rolled-channel form, with their flanges presenting inwardly. Suitable connection-plates or connection-angles are employed to attach these sills together, and a body-bolster (indicated at 4) affords another and important medium for tying the longitudinal sills, as well as affording a support therefor. Corner-posts 5, preferably in the form of angle-bars, extend upwardly to support the corners of the car, while intermediate posts 6 rise from the end sill for the same purpose. The end wall 7 of the car is secured to these corner and intermediate posts, said end wall resting upon brackets 8, arranged on said posts, said brackets carrying cleats 9, to which are secured the inclined floor-boards 10.

11 indicates a floor-beam, preferably in the form of an angle extending transversely the floor of the car and supported by floor-supports 12, which incline downwardly and out-

wardly and are secured by connection-plates 13 to the center sills. The ends of floor-beam 11 project outwardly beyond the side walls of the car and are secured to the web of one of 5 the Z-bar diagonals hereinafter described.

14. indicates a cover-plate for the bolster, upon which is arranged a floor-brace 15. (See Fig. 3.)

16 indicates angles secured by suitable connections to the side and center sills, which angles tie said sills and also form floor-supports.

17 indicates the side hopper-plates, secured at their upper edges to the side sills and provided along their inclined edges with inturned 15 flanges 18, which form floor-supports and to which the floor-boards 10 are secured.

19 indicates straps whose ends are bent up and secured to the outer faces of the inclined hopper-plates, said straps tying said hopper-20 plates in position. Angles 20 and 21 are also riveted to the lower ends of the flanges of the inclined hopper-plates for bracing the structure and forming floor-supports. These angles are held in position by corner-bands 21^a.

25 A transverse ridge-piece 22 is provided to tie the side and center sills and also form means of attachment of the floor-boards 23, which form the inclined walls of the transverse ridge.

30 A hood 25 is arranged above the center sills where said sills pass through the lower portion of the car-body, said hood being preferably formed by two boards oppositely inclined, which are secured at their ends to the 35 floor-boards 10 and which are supported throughout their length by inverted-V-shaped blocks, as is well understood.

26 indicates vertical hopper-plates forming the inner hopper-walls, said plates being secured to the outer faces of the webs of the 40 center sills and extending some distance along said center sills, said plates being preferably deepest at their middle portions and inclined at their lower edges, said inclinations coinciding with the inclined lower edges of the 45 hopper-plates 17. The lower edges of these plates 26 are flanged inwardly, as at 27, (see Figs. 6 and 7.) said inwardly-extending flanges forming, substantially, the tension-flanges of 50 the plates. These plates 26, in addition to forming the inner hopper-plates for preventing the load from interfering with the door or the brake-operating mechanism, also form the webs of a plate-girder structure by being attached to the center sills, the upper 55 flange of the center sill forming the compression-flange, while the flange 27 forms the tension-flange of the girder. In this way the center of the car is made extremely strong, the 60 girder being made deepest at its middle portion, the deep web of the girder being utilized as the side wall of the hopper-opening. The inclined ends of the plates 26 are likewise flanged, as at 27^a, (see Figs. 4 and 7.) said 65 flange 27^a being presented outwardly, so as to afford a support for the floor-boards 10.

If desired, batten-plates 28 or lattice-bars

may be connected to the bottoms of the center sills at suitable points for tying said center sills together.

Any suitable construction of hopper-door 70 may be used in connection with my improved car, said doors being operated by appropriate mechanism.

The side sills 3, to which I have referred, 75 form the lower chords of a trussed structure of which the rolled members 30, substantially in the form of rails located at the upper edge of the side walls of the car, form the upper chords. These chords have vertical posts 80 connected to them, the posts 31 being in the transverse plane of the body-bolster and preferably consisting of two parallel Z-bars, with their outer flanges presented away from each other and their inner flanges presented toward each other. (See Fig. 8.) It is obvious 85 that this post can be made of a single pressed or bent piece of metal. In this manner the planks or boards 32, which form the side walls of the car, may be directly secured to the inner flanges without the use of furring-strips, 90 ready access being obtained to the securing devices.

A connection-plate 33 is secured to the side sill, and to this connection-plate the outer 95 flanges of the transom-post 31 are riveted. By reason of said flanges projecting in opposite directions and away from each other easy access may be had to the rivets for the purpose of driving the same. In fact, a riveting-100 machine may be employed to make the connection between the members of this post and the connection-plate 33.

The top chord 30, to which I have before referred, is preferably in the form of an angle-bar whose horizontal flange or member extends inwardly, while its vertical flange extends downwardly. Inside of this vertical flange is riveted a connection-plate 34, and to this connection-plate are riveted the outwardly-disposed flanges of the post 31.

35 indicates a vertical post, preferably in the form of a Z-bar, which is secured to the bottom chord through the medium of a plate 36 and to the top chord 30 through the medium of the connection-plate 37. This post 35 is preferably located in the center of the car.

38 indicates an intermediate post connected to the bottom chord through the connection-plate 39 and to the top chord 30 through the medium of the connection-plate 40.

41 indicates a diagonal, preferably in the form of a Z-bar, whose outer flange is riveted to the connection-plates 36 and 40, and 42 indicates a diagonal, preferably in the form of a Z-bar, whose outer flange is riveted to the connection-plates 39 and 34. It will be noticed that these diagonals 41 and 42 are inclined in the same direction, and assuming 130 that we consider this side framing composed of the top chord 30, the bottom chord 3, and the Z-bars as a trussed structure, these diagonals 41 and 42 will be placed in tension.

under load, and preferably so. Otherwise the section of the **Z**-bars, if placed in compression, would have to be considerably increased in order to safely act as columns.

5 In order to brace the end of the car, I provide a connection-plate 43 at the end of the side sill, to which and to the connection-plate 34 is riveted a diagonal 44, preferably in the form of a **Z**-bar.

10 By using **Z**-bars in the construction of the vertical posts and diagonals, attaching devices, in the form of rivets or bolts between said parts and their respective connection-plates, can be most conveniently manipulated—in fact, in instances where rivets are used by a machine-riveter. The attaching devices between the inner flanges of said **Z**-bars and the boards forming the side walls of the car are also of easy access and can be conveniently manipulated. So far as I am aware I am the first to employ **Z**-bars for use as vertical posts and diagonals in a trussed structure for car-bodies. Furring-strips 45 are preferably placed in the angle 30 for the purpose of nailing or bolting the top boards thereto, said furring-strips of course being in short lengths and serving as fillers.

Having thus described my invention, what I claim, and desire to secure by Letters Patent, is—

30 1. The combination with the inclined hopper-plates provided with inturned flanges at their lower edges for supporting the inclined floor of the car, and straps which extend under the inclined floor, their ends being bent up against the outer faces of said inclined hopper-plates; substantially as described.

2. The combination with the side sills, of inclined hopper-plates secured thereto, the lower inclined edges of said hopper-plates being flanged inwardly to support the inclined floor of the car, and straps for tying said hopper-plates in position; substantially as described.

45 3. The combination with a center sill, of a plate 26 provided with a flange 27 on its lower edge, and a flange 27^a on its inclined edge, said latter flange forming a floor-support; substantially as described.

50 4. The herein-described side framing for cars, the same consisting of upper and lower

chords, posts and diagonals, said posts and diagonals being in the form of **Z**-bars; substantially as described.

5. In a framing for car sides, the combination with upper and lower chords, of **Z**-bars, vertical posts therebetween, **Z**-bar diagonals, and connection-plates; substantially as described.

6. A side framing for cars consisting of a side sill forming the lower chord of a trussed structure, a rolled member forming the upper chord of the trussed structure, parallel **Z**-bars forming a vertical post in the transverse plane of the bolster, and intermediate posts and diagonals; substantially as described.

7. A trussed side frame for cars comprising a channel side sill forming the lower chord, an angle-rail forming the upper chord, **Z**-shaped vertical posts and diagonals, connection-plates for securing said posts and diagonals to the upper and lower chords, and a side wall which is secured to said vertical posts and diagonals; substantially as described.

8. A trussed side frame for cars comprising a channel side sill forming the lower chord, an angle-rail forming the upper chord, **Z**-shaped vertical posts and diagonals, connection-plates for securing said posts and diagonals to the upper and lower chords, a side wall which is secured to said vertical posts and diagonals, and furring-strips between the angle-rail and the side wall; substantially as described.

9. In a trussed side framing for cars, the combination with a channel side sill, vertical posts and diagonals secured thereto, and an angle-rail to which the upper ends of said posts and diagonals are secured, said angle-rail having its horizontal member extending inwardly and its vertical member extending downwardly, furring-strips inclosed by said members, and a side wall which is secured to said furring-strips and to said vertical posts and diagonals; substantially as described.

In testimony whereof I hereunto affix my signature, in the presence of two witnesses, this 14th day of August, 1900.

GEORGE I. KING.

Witnesses:

W.M. H. SCOTT,
F. R. CORNWALL.
